CLAIM

The ornamental design for a hinge, as shown and described.

DESCRIPTION

FIG. 1 is a front, side perspective view illustrating our new design.

FIG. 2 is a side elevation view thereof.

FIG. 3 is a rear elevation view thereof.

FIG. 4 is a side elevation view from the side opposite the one shown in Figure.

FIG. 5 is a top plan view thereof.

FIG. 6 is a front elevation view thereof; and,

FIG. 7 is a bottom plan view thereof.

The broken lines are included for illustrative purposes and form no part of the claimed design.
